CLAIM

The ornamental design for a lattice for a gate, as shown and described.

DESCRIPTION

FIG. 1 is a perspective view of a lattice for a gate.

FIG. 2 is an enlarged perspective view of the lattice for a gate shown in the broken line circle of FIG. 1.

FIG. 3 is a side view of the lattice for a gate shown in FIG. 2.

FIG. 4 is another side view of the lattice for a gate of FIG. 3 shown in a different orientation; and,

FIG. 5 is another side view of the lattice for a gate of FIG. 3 shown in a different orientation.

The other orientations of the lattice for a gate of FIG. 1 are mirror images of the lattices shown in FIGS. 3–5.

The side views of the lattice for a gate on the opposite side of the lattice for a gate are identical to those shown in FIGS. 3–5.

The broken line showing of the remainder of the lattice for a gate is included for the purpose of illustrating environmental structure and forms no part of the claimed design. The dash-dot-dash broken lines depict the limits of the claim and form no part of the claimed design.
